(57) **CLAIM**

The ornamental design for a wheel rim for vehicle, as shown and described.

DESCRIPTION

1. Wheel rim for vehicle

1.1 : Perspective

1.2 : Front

1.3 : Left side view

1.4 : Rear view

1.5 : Right side view

1.6 : Top

1.7 : Bottom

The present design relates to a wheel rim for vehicle, as illustrated in the annexed drawings in which: FIG. 1.1 is a perspective view of the wheel rim for vehicle of the present design; FIG. 1.2 is a front view thereof; FIG. 1.3 is a left side view thereof; FIG. 1.4 is a rear view thereof; FIG. 1.5 is a right side view thereof; FIG. 1.6 is a top view thereof; and FIG. 1.7 is a bottom view thereof; Figures that show the design most sufficiently: front and rear views.
